UNITED STATES PATENT OFFICE.

JOHN A. TOPPING, OF NEW YORK, N. Y.

SHINGLE AND ROOF MADE THEREWITH.

Application filed January 20, 1925. Serial No. 5,616.

This invention relates to shingles and roofs made therewith.

One of the objects is to improve the appearance of roofs.

Another object is the provision of an improved means inherent in the shingle structure, to fasten and hold the intermediate portion of the butt or exposed end of the shingle in place when laid upon the deck of a roof.

A further object is to provide a flexible shingle which will bend downwardly in a straight line near its lower edge between its fastening means by the application of the fastening members or tongues in position with respect to adjacent shingles of the course below, thereby to give the appearance of an unusually thick shingle bridging the gap between adjacent shingles of said lower course.

A still further object is to provide a substantially rectangular shingle having two oblique slits in one edge to provide tongues, which serve as fastening means in cooperation with adjacent underlying shingles, and a pair of similar fastening means on another edge of said shingle, the pairs of slits and fastening tongues provided thereby on the respective edges, being different distances apart in accommodation for gaps of varying widths between shingles of an underlying course.

Another object is to provide fastening tongues cut from the lower butt edge of the shingle to hold the butt of the shingle down when the shingle is laid.

Other objects and advantages of the invention will become apparent to persons skilled in the art, from a consideration of the following description when considered in connection with the accompanying drawings forming a part hereof, wherein:

Figure 1 shows a plurality of the improved shingles laid upon a deck to form a roof with wide gaps between adjacent shingles of a course.

Figure 2 is a similar view showing the shingle reversed for courses in which the shingles are placed closer together.

Figure 3 is a section on the line 3—3 of Figure 1.

Figure 4 is a section on line 4—4 of Figure 1.

In all the views, the same reference characters are applied to indicate similar parts.

The shingle 5 which embodies the inven-

tion, is substantially rectangular, or it may have four equal angular sides forming a substantially perfect square, or it may be a parallelogram, as desired. The edges of the opposite ends of the shingle are provided with slits 6, 6' and 7, 7' to form tongues. The slits 6, 6' made in one edge of the shingle are separated a relatively short distance from each other. Slits 7, 7' are separated a greater distance apart. The object of the slits is for the purpose of forming tongues or parts 8 that may be made to extend from the lower margin edge 9 of the exposed portion of the shingle. The intervening portion 10 of the edge between the tongues 8 of the shingle corresponds in length with the gap 11 which is the space between the shingles 12 and 13 of the course below. It will be apparent that all of the slits 6, 6', 7, 7' are inclined toward the central zone area of the shingle. This is done so that the tongues 8 may point outwardly with respect to the axis of the shingle.

In laying the shingles, the course below containing the shingles 12 and 13 are separated a distance apart, depending upon the distance between the slits 6, 6' or 7, 7' in one or the other edge of the shingle.

When the roof is to be laid as shown in Figure 2, the end containing the slits 6, 6' is placed downwardly for cooperation with the shingles in the course below. The tongues 8 are to be stuck under the edges of adjacent shingles in the manner shown, this part of the shingle then forming the butt or exposed end. The slits 7, 7' and tongues 8 when not in use are located in the upper edges of the shingle as shown in Figure 2. When the shingle is in this position, the tongues will perform no useful purpose.

In any event, a nail 14 is to be driven into the corner of the exposed or butt end of the shingle. When the tongues 8 are stuck under the vertical edges 15 of adjacent shingles in the course below, the parts 10 and 10' between the respective tongues is bent downwardly, as shown more clearly in Figure 3, and when viewed from the ground it gives the shingle the appearance of unusual thickness, and thereby the roof is enhanced by its improved appearance. The tongues made in the butt or exposed end of the shingle not only hold the butt end down and give a better appearance to the roof—they also serve as an agent or guide by which the shingles may be laid.

It is not necessary for my invention to have the slits made in opposite edges of the shingle or any two edges, as they may be made in one edge only. It is a matter of convenience, however, to make the slits in both edges because then the shingle will accommodate itself to the variations of separation between the shingles of the sub-course, in the manner described. It will be observed that the part 10 which is bent downwardly when the tongues are tucked under the edges of adjacent shingles makes contact with a second course below, and thus this part fully closes the gap between adjacent shingles of the first course below, so that rain or snow may not be driven between the shingles and the wind cannot enter to thereby blow the shingles from the roof.

While I have merely shown a single embodiment of my invention, for the purpose of clear disclosure, it is manifest, to persons skilled in the art, that changes in the arrangement and configuration of parts may be made within the spirit and scope of the appended claims.

Having described my invention, what I claim as new and desire to secure by Letters Patent is:

1. A shingle having a pair of oblique slits in one edge, both slits inclined toward the central area of the shingle to provide fastening tongues for the exposed end of the shingle when laid upon a deck.
2. A shingle having a pair of oblique slits in one edge, and another pair of slits in another edge, the members of said pairs of slits being different distances apart, and all said slits inclined toward the central area of the shingle to provide outstanding tongues.

3. A shingle, rectangular in form, with 40 slits in opposite edges, there being two slits in each said edge, and all of said slits inclined toward the central area of the shingle, the slits in one edge being farther apart than the slits in the other edge. 45

4. A roof composed of a plurality of like shingles, each shingle having slits in its exposed bottom edge, said slits inclined toward the central area of the shingle to provide a single angular tongue with each slit and with said tongues tucked under the respective vertical edges of adjacent shingles of a course below, and the edge between said tongues bent downwardly on a straight line into contact with a shingle of the second 55 course below.

5. A roof composed of a plurality of like shingles, each shingle having two tongues, each tongue made by a single slit without removing part of the shingle extending in 60 opposite horizontal directions from its bottom horizontal edge with said tongues under vertical edges of the respective adjacent shingles of the course below to hold the central part of the butt edge down. 65

6. A roof composed of a plurality of shingles laid in courses, each shingle having two spaced slits in its bottom exposed edge to provide angular tongues and said tongues tucked under and beneath the bottom side 70 edges of adjacent shingles of a lower course, the parts between the tongues lying in the space between adjacent shingles of the lower course.

In testimony whereof I have hereunto subscribed my name.

JOHN A. TOPPING.
